JOHN MARCHBANK, OF LANSINGBURG, NEW YORK, ASSIGNOR TO
WILLIAM H. LOW, OF SAME PLACE.

Letters Patent No. 73,822, dated January 28, 1868.

IMPROVEMENT IN FAUCETS.

The Schedule referred to in these Letters Patent and making part of the same.

TO ALL WHOM IT MAY CONCERN:

Be it known that I, JOHN MARCHBANK, of Lansingburg, in the county of Rensselaer, and State of New York, have invented certain new and useful Improvements in Molasses-Faucets; and I do hereby declare that the following is a full, clear, and exact description of the same, reference being had to the accompanying drawings, making a portion of this specification, in which—

Figure 1 is a front view of a faucet made according to my invention.

Figure 2 is a side view and partial section of the same.

Similar letters of reference indicate corresponding parts in both figures.

The object of this invention is to insure a perfectly tight closing of the faucet when not in use, and also to secure the retention of the gate thereof in position when the same is raised to open the faucet.

The invention consists in so combining a guide-brace with the tubular body of the faucet, and the gate thereof, that the said brace will operate to firmly hold the gate in position, either to close or open the faucet.

The invention further consists in certain novel arrangements of inclined planes upon the outer side of the gate, and in relation with the transverse guide-brace in front thereof, whereby the desired objects are attained with less friction upon the brace than if such inclined planes were dispensed with.

The invention further consists in a stop, so applied to the gate, and in such relation with the brace, that any accidental displacement of the gate in opening the same is effectually prevented.

To enable others to understand the construction and operation of my invention, I will proceed to describe it with reference to the drawings.

A represents the tubular body of the faucet, of any suitable form or construction, and B shows the gate pivoted at one side of the face thereof, as shown more fully in fig. 1. Secured in front of the gate is the transverse bar C, which not only serves as a guide to assist in retaining the gate in position while being moved, but also as a brace to hold the gate properly in place whether in position to open or close the faucet. In order to insure the perfect closing of the orifice or mouth a of the faucet, when the gate is pushed downward, without the friction attendant upon a swing pressure of the gate against the brace C, during its entire movement, an inclined plane, b, is formed upon the upper part of the front or face of the said gate, in the position shown more fully in fig. 1, and in such manner that when the gate is forced downward, the aforesaid inclined plane b being pressed against the guide-brace, will force or crowd the gate tightly against the front of the body A, over the orifice a, thus effectually closing the faucet. A similar inclined plane, c, but placed somewhat nearer the pivot of the gate, in such relation with the guide-brace that when the gate is raised in the usual manner to open the faucet, the said inclined plane c will bind against the brace, and the gate being thus snugly held between the brace and the upper part of the face-end of the body A, will be prevented from falling by its own weight when the faucet is in use. Projecting forward from the lower part of the front of the gate is a stud, a*, which, by limiting the upward movement of the gate, in case the inclined plane c should be carried past the brace, effectually prevents the accidental displacement of the gate in thus opening the faucet.

What I claim as my invention, and desire to secure by Letters Patent, is—

1. The arrangement of the guide-brace C in relation to the gate B and the body A, substantially as and for the purpose herein set forth.
2. The inclined plane b, provided upon the gate, and arranged in relation with the body A and the guide-brace C, substantially as and for the purpose specified.
3. The inclined plane c, arranged upon the gate, and in relation with the body A and guide-brace C, substantially as and for the purpose specified.
4. The stud a*, arranged upon the gate, and in relation with the guide-brace, substantially as and for the purpose specified.
